STEPLADDER

Vincent J. Buckner, Washington, D. C.

Application March 20, 1946, Serial No. 655,676

1 Claim. (Cl. 228—36)

(Granted under the act of March 3, 1883, as
amended April 30, 1928, 370 O. G. 757)

1

The invention described herein if patented, may be manufactured and used by or for the Government of the United States for governmental purposes without the payment to me of any royalty thereon or therefor.

The present invention relates to step ladders and particularly to one of suitable construction for use in aiding persons to climb into and out of upper berths.

It is a primary object of the invention to provide a ladder of strong and rigid construction, preferably of tubular metal for imparting great strength with light weight.

A further object of the invention to provide a ladder having folding steps thereon capable of folding into a compact construction enabling easy handling and stowage.

Another object of the invention is to provide permanent rungs in a ladder having foldable steps whereby the ladder frame is made rigid.

A further object of the invention is to provide a ladder wherein the rungs are so arranged as to support excessive loads on the steps.

It is still another object of the invention to provide a locking device for the folding steps of a ladder to hold the same rigidly open independently of the position of the ladder so that on a weaving, vibrating or unstable floor, as may be encountered on a train or ship at sea, the steps will be locked open to provide maximum safety, and a locking mechanism operative to hold the steps in folded position whereby to provide a compact structure for handling and to prevent noisy rattling when stowed.

For an understanding of these as well as related and inherent objects, reference is made to the step ladder shown in the accompanying drawings which are intended to be illustrative and not limiting.

Figure 1 is a sectional view through the center of the ladder taken on the line 1—1 of Figure 2.

Figure 2 is a front elevation of the ladder unfolded and in position for use.

Figure 3 is a detail of one of the step plates showing the mounting and the arc through which the step may be rotated.

Figure 4 is an enlarged view in side elevation of the hook shaped upper end of a side member.

Figures 5, 6, 7, 8 and 9 are views taken on lines 5—5, 6—6, 7—7, 8—8, and 9—9 of Figure 2, and

Figure 10 is an enlarged front elevation of the foot of the ladder.

With reference to the drawings, the ladder includes two side members 11 bound together by a series of vertically spaced horizontal rungs 12,

2

which are shown as bars of circular cross section, welded or otherwise rigidly fastened at each end to a side member, binding the same into a single rigid ladder structure. The side members 11 as shown in Figure 8 are preferably of metal, hollow, and of somewhat rectangular cross section modified by rounded edges and have grooves for nesting other parts as further described herein. The rungs 12 may be of "tubular" metal, but they as well as the side members may be constructed of solid non-metallic materials if desired. Tubular metal is preferred only because of its greater strength and rigidity coupled with relatively light weight, which are highly desirable characteristics in a ladder subject to much handling and which must be stowed in minimum space and used under conditions requiring great rigidity and safety.

The upper end of each side member preferably terminates in a hook-like bend 13 which is intended to curve over a horizontal bar forming part of an upper berth (not shown) for purposes of safely supporting the upper end of the ladder.

The bottom of each side member rests on a foot pad 14 of resilient material such as rubber, plastic or hollow metal to secure the bottom of the ladder against slipping and form a firm gripping surface with the floor 15.

Pivotedly mounted through pins 16 fitted in holes in the side members 11 immediately above the fixed rungs 12 and in complementary horizontal bores in each end are folding step plates 17. These step plates have a hollowed or ground out portion 18 on the underside in which the rung will snugly fit when the step is rotated into folded position as shown in the dotted line position of Figure 3. The step plate 17 is mounted above the fixed rung 12 with sufficient clearance to allow the step plate to be easily rotated about the rung to open or closed position but sufficiently close to the rung to bear the weight of a person on the step plate when sufficient to cause the plate to sag into contact with the fixed rung.

The side members 11 are provided with complementary rectangular grooves 19 in the forward edge of each side member and sliding rods 20 of similarly rectangular cross section are fitted in the grooves for easy reciprocation therein, the rods being shorter than the grooves to allow reciprocation sufficient to effect folding and locking as hereinafter described.

Pivotedly pinned to each sliding rod and the end of each step plate, through pins 21, are arms 22 fixed so that reciprocation of the sliding rods 20 causes each step plate to rotate on its pivots 16. The arms 22 are pivoted to the sliding rods

3

20 at points so disposed that when the rods are in the extreme upper ends of the grooves the step plates 17 will be open or ready for use, as shown in Figures 1, 2 and 3. As noted, the rods 20 fit smoothly in the grooves 19 and within the general overall contour of the side members, or as shown in Figure 8, the rectangular cross section of the side members and sliding rods are complementary, so that no portion protrudes. It will be evident, however, that any other shape of groove and sliding rod may be used. To retain the rods in the grooves a series of clips or brackets 23 are fixed over the groove to each face of the side members.

The sliding rods are shorter than the length of the groove sufficient at least to allow the step plates to be folded into closed position when the rods are at substantially the lower end of the grooves 19 but are of sufficient length to cooperate with a locking device 24 horizontally positioned between the lower ends of the side members. The locking device 24 includes a horizontally disposed housing which may be of similarly rectangular section as the side members and is divided by plate brackets 25 and 26 bored to receive and support therein horizontally sliding and locking bolts 27. The outer ends 28 of the bolts 27 are of smaller diameter than the remainder of the bolt adapted to slide across the grooves 19 in the path of the sliding rods and are fitted in holes 29 bored in the walls of the side members defining the grooves 19. The central portions of the bolts 27 have permanently fixed collars or shoulders 30. A spring 31 surrounds each bolt and is confined between the shoulder 30 and the bracket 26 to urge the bolt 28 into the groove 19 and hole 29, when the sliding rod has been raised above the bolt. The sliding rods are therefore, made the same length as the distance between the bolt and top or upper end of the groove so that when the bolt is thus fully closed the sliding rod is locked in the open position with the step plates attached thereto held rigidly open. The housing 24 on the inner side of the ladder is of smaller section 31 at the middle and has a slot 32 cut therein extending the distance of the depressed middle portion 31 to receive protruding ears 33 attached to inner ends of the bolts 27. Thus by pulling the ears 33 towards each other the bolts 27 are slid inward against the pressure of the springs and the ends of the bolts 28 are thus withdrawn from the grooves freeing them to downward movement of the sliding rods when the steps are to be folded. In the position shown in Fig. 7, with the rods 20 extending across the groove the bolt under the spring pressure will bear against the rod 20 itself and prevent noise or rattling of the rods and movement of the step plates attached thereto while in the closed position. It is therefore, apparent that the locking device is operative in both open and closed positions regardless of the position of the ladder.

To prevent open sharp portions from snagging clothing when the ladder is used, the outer por-

4

tion of the groove is desirably terminated at the point 35 where the locking device joins the side member 11 and the inner portion bends inward, whereby the ladder is smooth from this point downward. In this arrangement the lower end of the sliding rod is bent inward slightly, as shown in Figure 7, the dotted lines thereof indicating the bent sliding rod in raised position.

Hand grips 36 are attached to the sliding rods at a convenient height for grasping the ladder for mounting, and serve also to facilitate movement of the sliding rods to open and close the steps.

Having described my invention and illustrated an embodiment thereof, what I claim is:

A step ladder having a pair of side members secured in spaced relationship by a plurality of fixed and substantially uniformly spaced rungs, in combination with step plates pivoted at their ends to said side members independently of said rungs, said step plates being pivoted surmounting of said rungs in a manner whereby said rungs will serve to support loads on said steps when of sufficient magnitude to cause a central downward deflection of said steps, means for axially rotating said steps on their pivots in unison from an open usable position with their planar surfaces at a predetermined angle with respect to the front and rear planes of said ladder to a folded stopped position in abutment with said rungs and within said planes of the ladder, releasable locking means carried by said side members automatically operable to hold said step actuating means in open and folded step positions, and manually operable means for releasing said locking means.
